UNITED STATES PATENT OFFICE.

PETER H. KESEBERG, OF HAMBURG, GERMANY.

SPRING BED-BOTTOM.

SPECIFICATION forming part of Letters Patent No. 275,497, dated April 10, 1883.

Application filed February 14, 1883. (No model.) Patented in Germany April 23, 1880, No. 12,402; in Belgium December 15, 1881, No. 5,634, and in Austria-Hungary December 31, 1881, No. 35,220 and No. 43,809.

To all whom it may concern:

Be it known that I, PETER HEINRICH KESEBERG, of the city of Hamburg, in the Empire of Germany, have invented certain new and useful Improvements in Spring Bed-Bottoms, (for which Letters Patent have been granted to me in Germany, No. 12,402, dated April 23, 1880; Austria-Hungary, Nos. 35,220 and 48,309, dated December 31, 1881, and Belgium, No. 5,634, dated December 15, 1881,) of which the following is a specification.

This invention has reference to improvements in spring bed-bottoms; and the invention consists of a bed-bottom composed of longitudinal and transverse slats, the latter carrying spiral springs, which are provided at their upper ends with wooden or metallic blocks that are connected by longitudinal and transverse metallic bands or straps. The head-section of the bed-bottom is made vertically adjustable by placing the springs on inclined strips, which are adjusted higher or lower by a suitable adjusting mechanism, as will be more fully described hereinafter.

In the accompanying drawings, Figure 1 represents a side elevation, and Fig. 2 a plan, of a bed-bottom for single or double beds. Fig. 3 is a plan of a bed-bottom for narrower beds—such as ship and car berths. Figs. 4 and 5 are end elevations of the adjusting mechanism of the head-section. Fig. 6 is a side elevation of the head-section with its adjusting mechanism. Figs. 7 and 8 are respectively a vertical central section and a bottom view of one of the spiral springs and its connection with the top block.

Similar letters of reference indicate corresponding parts.

My improved bed-bottom is constructed of longitudinal base-slats *a a*, to which a number of transverse slats, *b b*, are applied. The spiral supporting-springs *d* of the bed-bottom are seated at their lower ends in circular grooves of the transverse slats *b b*, and secured at their upper ends to corresponding grooves of wooden or sheet-metal heads or blocks *e e*, of round or polygonal shape, which blocks are attached to the springs by means of pivoted catches *e'*, (shown in Figs. 7 and 8,) or by any other equivalent fastening device. The blocks *e* are con-

nected by longitudinal and transverse sheet-metal bands or straps *f f'*, which are retained in bottom grooves at the underside of the blocks *e e*, and secured thereto by rivets, staples, or otherwise. The sheet-metal straps or bands *f f'* impart the required degree of stiffness and rigidity to the bed-bottom and transfer the pressure from one top block to the adjoining blocks, so as to call a number of springs into action when pressure is exerted thereon.

The head-section *a'* of the bed-bottom is so arranged that the longitudinal bands *f* run continuously through from the main part of the bed-bottom to the blocks *e* of the head-section, the transverse base-slats of which latter are, however, not supported on the longitudinal base-slats *a a*, but on inclined strips *a'*, which are guided by their grooved front ends on short rods *a*, attached to the base-slats *a a*. The inclined head-strips *a'* are either notched at the under side and supported at a greater or less angle of inclination to the base-slats *a a* on a transverse strip, *h*, which is secured to slide-blocks *h'*, that may be moved forward or backward on the rods *a*, as required, for the adjustment of the head-section, as shown clearly in Fig. 1, or the head-section *a'* may be supported by one or two toothed rods, *i*, applied to a transverse piece, *i'*, which latter is pivoted to the inclined adjustable strips *a'* of the head-section *a'*, as shown in Figs. 4, 5, and 6, in which case the toothed rod or rods *i* are locked by means of spring-catches *i''*, that may be withdrawn by means of strings *i'''* or otherwise from the teeth of the rod or rods, so as to facilitate the raising or lowering of the head-section *a*. The inclined strips *a'* are guided in the latter construction in the same manner on the guide-rods *a* of the base-slats *a a* as in the construction shown in Fig. 2.

When the bed-bottom is used for narrow beds or berths the number of transverse base-slats may be reduced—in fact, only two at the head and foot end are required, as shown in Fig. 3. The longitudinal straps or bands *f f'*, however, are continued through the adjustable head-section *a'*, said bands forming the connecting-links of the main part and head-section. In place of the metal bands or straps, cane-straps may be used.

The advantages of my improved construction are that the head-section may be adjusted to different inclinations, that the entire bed-bottom may be quickly assembled and put together, and that any one of the spiral springs may be readily exchanged in case of breakage or wear.

Having thus described my invention, I claim as new and desire to secure by Letters Patent—

1. As an improvement in bed-bottoms, the combination of the longitudinal slats *a a*, transverse slats *b b*, spiral supporting-springs *d d*, top blocks, *e e*, secured to the upper ends of the springs, and longitudinal and transverse straps or bands *f f'*, secured to the under side of the blocks, substantially as set forth.

2. The combination of a bed-bottom constructed of longitudinal slats *a a*, transverse slats *b b*, spiral springs *d d*, blocks *e e*, and longitudinal and transverse bands or straps *f f'*, with a head-section, *a'*, connected to the main portion by the longitudinal straps *f*, and being

supported on inclined and guided base-strips *a'*, provided with mechanism for adjusting the head-section higher or lower, substantially as specified.

3. As an improvement in spring-bed bottoms, the combination, with the main portion of the bed-bottom, of an inclined head-section, the spring-supported head-blocks of which are connected to the head-blocks of the main portion by longitudinal bands or straps, said head-section having inclined base-strips guided on the base-slats of the bed-bottom, and mechanism for adjusting the base-strips higher or lower thereon, substantially as specified.

In testimony that I claim the foregoing as my invention I have signed my name in presence of two subscribing witnesses.

P. H. KESEBERG.
